CLAIM

The ornamental design for an accident identity kit, as shown and described.

DESCRIPTION

FIG. 1 is a closed view of the accident identity kit.

FIG. 2 is a closed opposite view of the accident identity kit.

FIG. 3 is a top plan view of the accident identity kit, in the open position.

FIG. 4 is a view from one end of the kit shown in FIG. 3.

FIG. 5 is a view from the opposite end of the kit in FIG. 3.

FIG. 6 is a view from the side of the kit in FIG. 3; and,

FIG. 7 is a view from the opposite side of the kit in FIG. 3.

The broken line portions of the disclosure are for illustrative purposes only and form no part of the claimed design.
